United States Patent Office.

MILTON F. ADAMS, OF BOSTON, ASSIGNOR TO E. B. WELCH, OF CAMBRIDGE, MASSACHUSETTS.

Letters Patent No. 99,047, dated January 25, 1870.

IMPROVEMENT IN PRINTING-TELEGRAPHHS.

The Schedule referred to in these Letters Patent and making part of the same

To whom it may concern:

Be it known that I, MILTON F. ADAMS, of Boston, in the county of Suffolk, and State of Massachusetts, have invented a new and useful "Automatic Printing-Telegraph Apparatus;" and do hereby declare the following to be a full, clear, and exact description thereof, reference being had to the accompanying drawings, making a part of this specification, in which—

Figure 1, of Sheet No. 1, is a front view of the apparatus embodying my invention.

Figure 2, of Sheet No. 2, is a plan of the upper portion of the apparatus, representing the printing-arrangement on a circular platform.

Figure 3, of Sheet No. 2, is a plan view of a second platform, placed below that shown in fig. 2.

Figure 4, of Sheet No. 3, is a horizontal section on the line $x x$, fig. 1.

The object of my invention is to transmit communication, in printed form, over telegraph-wires, and without the use of an attendant, by means of an automatic working apparatus, thus enabling brokers, merchants, or heads of departments, &c., to correspond directly and privately with their agents in distant parts.

And my invention consists in the employment of a type-wheel, bearing on its face as many letters, figures, and signs as there are on the keys of the key-board, and an escapement, armature, and magnet, by which the type-wheel is rotated, and impression-roller, around which the paper to be printed is guided and held by fingers or frame, said impression-roller being thrown against the type-wheel by means of levers and cams on cam-wheel, the latter to be rotated by a train of wheels, drum, and weight, and stopped or released by means of escapement-wheels, escapement, and second magnet. The second magnet is connected by conducting-wire with the base of key-board, while the magnet operating on the type-wheel is in electric communication, by means of a conducting-wire, with the break-spring, or drum.

Referring to the drawings—

A is a base-plate, on which a key-board, B, is arranged, containing forty-one keys, marked as explained below, to economize space; and to make it also convenient for the operator, a number of the keys is placed upon and between every two of the larger and forward keys, like a piano key-board.

The keys move on pivots, and, with their narrow and tapering ends, project to the rear, toward a large metallic drum, C, which being placed parallel to the keys, is provided with projecting pins, $a a a$, corresponding in number to the keys. At one end, and around its circumference, are inserted breaks, of non-conducting material, $b b b$, forty-one in number, and

a break-spring, c, placed in such a position as to be in contact with the drum C, and pressed against the latter by means of a spring, to which the conducting-wire m is attached, transmitting the electric current to the drum, when it touches the space between two breaks, $b b$, and breaks the current when coming in contact with one of the insulator-breaks b .

The drum C is set in motion by a weight or spring acting upon a drum, e, and a train of wheels, $f g h i$, the ratchet-wheel k , on drum e, and catch k' , being attached to wheel f , for the purpose of allowing the drum C to move in one direction only.

The flier l is attached, for regulating the motion.

The drum C is fitted loosely on its shaft, and rotates with the same by means of friction-break d , in such a manner that when the motion of the drum C is stopped by one of their projecting pins coming in contact with a raised key, the shaft moves on, but as soon as drum C becomes released, the friction of break d causes the drum to move with the shaft.

The standards 1, 2, and 3, support a platform, D, on which are placed two sets of magnets, E and F, with the escapements G and H, and escapement-wheels G' and H'. The escapement-wheel H' is connected with a train of wheels, $f' g' h' i'$, and drum e', which is operated by weight or spring.

Above platform D is placed another platform, K, and supported in a suitable manner, on which the printing-process is accomplished.

The escapement-wheel G' having forty-one indentations or teeth, is fitted on the shaft s, which, passing through platform K, supports, at its upper portion, the type-wheel L. The type-wheel is provided on the face with the same letters, figures, and signs as there are on the keys, and pins on the drum, and arranged in a suitable order, it receives the ink from the inking-rollers t.

The escapement-wheel H' is fitted on shaft u, which has attached to its upper portion the wheel N, having as many cams as there are indentations on wheel H, the number of them being immaterial.

The cams of wheel N operate on end of lever P, on the opposite end of which is attached a roller, R, around which the paper to be printed on is passed, and the forked-shaped fingers S, for holding the paper against roller R. The latter receives, also, a rotary motion, by means of spring T acting against a ratchet underneath and forming a part of roller R, the spring T being brought in action by the backward motion of roller R.

The motion of cam-wheel N throws the roller R, with the paper, against the type-wheel L, while the spring T frees the roller R from type-wheel L, and gives the former a rotary motion, thus pushing the paper along, and spring T returns the lever P, through

its pressure on fingers **S**, into proper position to be acted upon by the following cams.

In the rear of base-plate **A** are placed three binding-screws, **V** **V'**. **V** is for receiving the wire for type-wheel circuit, while **V'** is for that of the impression-circuit. After passing the binding-screws **V** **V'**, the wires may be united in one line, which passes off to a distant apparatus, or into the ground. The binding-screw **V'** receives the current from the battery, and carries it, by line **r**, to the standard of drum **C**.

For operating this apparatus, finger the keys representing the respective letters, figures, and signs. This will stop the drum **C** at a corresponding pin, **a**, the break-spring **c** resting on one of the insulated breaks **b**. The acting-key will touch the base of key-board, and thus an electric current becomes established, passing from battery, through binding-screw **V'**, and wire **r**, to the drum **C**, and from there, through pin **a**, to the opposite key and base of key-board, and through wire **n** to magnet **F**; from there, through the impression-current to the binding-screw **V'**, and through the united line into the ground. But during the electric action, the magnets **F** will attract the opposite armature of escapement **H**, and set free the escapement-wheel **H'**, to be moved by the train of wheels, weight, or spring, and by means of shaft **u**, causes the cam-wheel **N** to follow the motion, and act upon the lever **P**, throwing roller **R**, with the paper, against the type-wheel, for receiving the impression. Now, by releasing the key, this circuit becomes broken; the drum **C** commencing to revolve until stopped again, the break-spring **c** passing over the insulated breaks **b** **b**, and the intervening spaces, and opens and closes the circuit, which passes, by means of wire **m**, magnet **E**, and binding-screw **V**, to the united line, and to the ground, and from the battery through binding-screw **V'**, and wire **r**, to drum **C**; but as often as this circuit is changed, as often the magnets will operate the escapement **G**, escapement-wheel **G'**, and with it the type-wheel **L**.

In practice, it is understood that the key-board,

drum, and all parts shown in fig. 4, are in the hands of the party sending the message, while all the parts on the two platforms, as shown in figs. 2 and 3, are under the observation of the receiving-party; or there may be two apparatus, one on each end of the united line.

In arranging the letters, figures, and signs, I find the following method as most practical and time-saving:

Commencing at the right of key-board, and calling the first key "dot;" the next above, "blank;" the third below, 1, and so on, 3, 7, 5, 8, 4, 2, 6, 9, 0; "blank;" **G**, **B**, **I**, **T**, **O**, **L**, **C**, **Q**, **K**, **H**, **A**, & **V**, **D**, **E**, **M**, **S**, **R**, **N**, **W**, **T**, **F**, **J**, **U**, **X**, **Y**, **Z**. These letters, figures, and signs, are arranged in the same order on the type-wheel.

Having fully described my invention,

What I claim as new, and desire to secure by Letters Patent, is—

1. The combination of key-board **B**, drum **C**, insulator-breaks **b**, break-spring **c**, train of wheels, with magnet **E**, escapement **G**, wheel **G'**, and type-wheel **L**, in the manner and for the purpose substantially as described.

2. The combination of type-wheel **L** with roller **R**, lever **P**, cam-wheel **N**, escapement **H** and wheel **H'**, and magnet **F**, in the manner and for the purpose as stated.

3. The combination of key-board **B**, drum **C**, insulator-breaks **b**, break-spring **c**, magnet **E**, escapement **G**, type-wheel **L**, with roller **R**, lever **P**, cam-wheel **N**, escapement **H**, and magnet **F**, when arranged in the manner and for the purpose as set forth.

In testimony whereof, I have signed my name to this specification, in the presence of two subscribing witnesses.

MILTON F. ADAMS.
